(57) **CLAIM**

The ornamental design for a gateway as shown and described.

DESCRIPTION

FIG. 1 is a front top perspective view of a gateway showing our new design;

FIG. 2 is a rear top perspective view thereof;

FIG. 3 is a front bottom perspective view thereof;

FIG. 4 is a front view thereof;

FIG. 5 is a rear view thereof;

FIG. 6 is a side view thereof;

FIG. 7 is an opposite side view thereof;

FIG. 8 is a top view thereof; and,

FIG. 9 is a bottom view thereof.

The broken lines immediately adjacent to the shaded area define the bounds of the claimed design and form no part thereof. The remaining broken lines represent portions of the gateway that form no part of the claimed design.
